UNITED STATES PATENT OFFICE.

ALEXANDER G. WILKINS, OF MEADVILLE, PENNSYLVANIA, ASSIGNOR OF ONE-HALF TO ANDY L. DUNBAR, OF SAME PLACE.

BUTTON-SETTING INSTRUMENT.

SPECIFICATION forming part of Letters Patent No. 367,016, dated July 19, 1887.

Application filed September 3, 1886. Serial No. 212,606. (No model.)

To all whom it may concern:

Be it known that I, ALEXANDER G. WILKINS, of Meadville, Crawford county, Pennsylvania, have invented certain Improvements 5 in Button-Fastening Machines; and I hereby declare the following to be a full, clear, and exact description of the same, reference being had to the accompanying drawings, making part of this specification, in which—

10 Figure 1 is a front elevation of my improved machine. Fig. 2 is a side elevation, partially in section. Fig. 3 is a vertical cross section of the lower jaw. Fig. 4 is a plan of the lower face of the upper jaw. Fig. 5 is an end 15 view of a removable magazine to contain buttons and supply the button-conductor. Fig. 6 is a plan of the upper face of the lower jaw. Fig. 7 is a plan of the plate on which the magazine rests. Figs. 8 and 9 are details to 20 be referred to.

My invention relates to machines for attaching buttons to fabrics by means of staples, and has for its object to provide a hand or power machine for quickly and certainly se- 25 curing the buttons, all of which will be hereinafter fully described, and specifically set out in the claims.

In order that those skilled in the art may make and use my invention, I will proceed to 30 describe the manner in which I have carried it out.

In the drawings there is used for illustration a machine having one fixed and one movable jaw, though both jaws may be movable without departing from the spirit of my invention. 35 A movable jaw, B, is pivoted at C to a fixed jaw, A, the fixed jaw carrying the button and staple conductor and the movable jaw carrying the devices for upsetting the staples.

40 The button and staple feeding device proper is a reciprocating bar, D, which beats up and down on a bolt, D', secured at a in the extreme point of the upper jaw. To the front of bar D is secured a button-feeding plate, D", 45 having a slot, a', to receive the button-eyes, and connecting with a transverse slot, a", (see Fig. 4,) in which rest the staples as they pass to the fastening-point. On the front of plate D" is secured a spring escapement-detent, b, 50 turning on a pivot, b', and held in position by

a curved spring, b", and operated by means of a stop, b''', secured to the head of the machine. The dimensions of the slot a' and a" are such as to snugly receive the button-eye and staple and yet have no impediment to the downward gravity-feed. In the bar D, immediately back of slot a', is a groove or offset, g, into which the bight of the button-eye projects, to keep the button from turning as it slides down the conductor. 55

In a line at right angles to bolt D' the lower point of the head or stationary jaw of the machine is centrally bored, as seen at d, to receive the shank of a sliding upsetting-bolt, E, provided with a coiled spring, E', around the 60 projecting end of the shank, to keep said bolt E normally withdrawn to the position seen in Fig. 1. The head e of this bolt protrudes into a wide slot, e', cut vertically in the lower end of bar D, and the bolt is provided at e" with 65 a diagonal face resting against a diagonal face, e''', on the bar D, which faces, abutting against each other, act as cams to retract spring E' and throw the head e forward in the line of the feed of the button-eyes as bar D is forced upward, 70 in a manner hereinafter described. Immediately below a point in line with bolt E the button-feeding plate D" is provided on its face with a light spring-detent, f, designed to arrest and hold the button and staple just released by the escapement-detent b. 75

The movable jaw B has at its end a sliding yoke, F, (see Figs. 1 and 3,) whose sides clasp the sides of the jaw and move in milled or planed ways h h, and the lower plate, F', of 80 which is bored at h' to receive a headed bolt, G, secured rigidly to and projecting downwardly from the jaw B. A coiled spring surrounds bolt G, and one end of it bears against the head of the bolt, while the other end bears 85 against plate F', so that the yoke F is normally maintained by a spring-pressure in the position shown in Fig. 1. Pivoted in the heads of the yoke F at g are two jaws, H H, having depending tongues g' g', whose inside 90 lines are straight and parallel and have a light bearing against the ends of a transverse stud, h'', which passes through the upsetting-anvil I, which is screwed into the upper face of jaw B, centrally within the yoke F. The 95

anvil I is rectangular in cross section, and two sides of it lie close to two pins, *i i*, passing across the yoke F and connecting its two sides. These pins hug the square sides of the rigid anvil I and serve as bearings to steady yoke F in its reciprocation back and forth on bolt G. In the inside lines of the sides of yoke F, in a line with the upper meeting line of jaws H H, are cut half-funnel-shaped openings, and adjacent thereto in the meeting edges of jaws H H are half-funnel-shaped openings, and together these make up the funnel-shaped openings *k k*, which pitch toward the central line, the distance between the openings being substantially the distance between the points of the legs of the staples J, so that as the points of the legs of the staples approach the holes *k k* the tendency is to direct each leg centrally to an inwardly-beveled deflecting-surface and give them a preliminary upsetting, as seen in Figs. 3 and 7.

To provide for a continuous supply of buttons and inserted staples, I have made a rotary magazine, M, having circumferentially arranged a series of longitudinal pockets, *l*, designed to be brought consecutively in line with the feeding-plate D". This is accomplished by mounting the magazine on a pivot, *m*, supported by a bracket, *n*, secured to the face of the head. The supporting face of this bracket (seen in Fig. 8) is provided with a slot, which registers with slot *a' a''*, and each one of the receptacles or pockets is of a configuration to coincide with slots *a' a''* also, and grooves or recesses *o o*, to guide the bight of the button-eyes.

The operation is as follows: The staples are strung into the eyes of the buttons and the button-carrier is filled with them, one above the other, and the magazine is set upon the bracket after being filled with buttons and staples, while the buttons and staples are prevented from escaping through the button-magazine by the split ring N, which surrounds it and is hinged to a lug, *t*, and is to be withdrawn as the pivot *m* enters the bracket *n*. In this position the lowermost button rests against the escapement-detent *b*. The jaws are brought together, and as sliding bar D is forced upward the projecting end of the detent *b* is relieved from the stop *b''*, and the spring *b'* throws the inner end upward, so that a button may drop in the depression therein contained. The jaws are caused to recede, and as stop *b''* again strikes the outer end of the detent it changes its position, making the inner depression drop the contained button and arrest the superincumbent line of buttons. The released button falls along through slot *a* until arrested by spring-detent *f*, where it remains ready for attachment. The fabric is inserted between the jaws and the jaws brought together. The pressure upward of the yoke, sustained by the spring around bolt G, forces bar D upward, and as it moves, the cam-faces *e''* and *e'''*, com-

ing in contact, throw forward the bolt E until its end, bifurcated slightly at *p* to straddle the bight of the button-eye, lies immediately over the staple in the button held by detent *f*. The pressure continuing and the bar D and plate D" still receding, the end of bolt E presses so upon the staple held by detent *f* that the spring is overcome and the points of the staple drop against the fabric, through which they are forced, and into the primary deflecting holes *k k*, which start the legs across each other, as seen in Fig. 3. At about this time the pressure is such as to overcome the spring around bolt G, and yoke F begins to descend past the head of anvil I. When the yoke has so far descended that the ends of stud *h* pass the pivotal points *g g* of jaws H, the ends of said stud cease bearing on the parallel faces of the jaws and the end of the anvil throws the upper curved ends of the jaws apart and the partially-upset staple is pinched and the fastening completed between the anvil I and the bolt E, making with the fastening-staple shown and described in United States Patent No. 345,562, issued to me July 13, A. D. 1886, a most desirable and secure fastening for buttons to all kinds of fabrics.

Having thus described my invention, what I claim as new, and desire to secure by Letters Patent, is—

1. In a button-setting instrument, the combination, with an upper jaw, a reciprocating button and staple carrier secured thereto, and a sliding bolt mounted in said jaw and adapted to move in a line at right angles to the movement of the button and staple carrier, of an upsetting-anvil secured to the lower jaw of the machine and adapted to clinch the staples, substantially as set forth.

2. The reciprocating button and staple carrier D", bolt D', a reciprocating bar mounted on said bolt, detent *b*, and stop *b''*, in combination with the head A, substantially as set forth.

3. In a button-setting machine, the combination, with a jaw having a reciprocating button and staple carrier provided with slots *a' a''* and the offset or groove *q*, and a transverse reciprocating bolt attached to said jaw, of a movable jaw carrying an upsetting-anvil, substantially as set forth.

4. In a button-setting machine, the combination, with a button and staple carrier or chute and an anvil, of the button feeding and upsetting bolt having its end notched to straddle the button-eye, and means, substantially as described, to operate said bolt, substantially as set forth.

5. In a button-setting implement, the combination, with a button and staple carrier or chute and an anvil, of the button feeding and upsetting bolt having its end notched to straddle the button-eye, substantially as set forth.

6. The jaw B, in combination with the spring-yoke F, bolt G, having a spring, and central anvil, I, substantially as set forth.

7. The jaw B, in combination with the anvil I, yoke F, and pivoted jaws H, provided with the deflecting-holes k k , as specified. 20
8. The yoke F, and central anvil, I, in combination with pin h'' , passing through anvil I, and the jaws H H, all constructed, arranged, and operated as set forth. 5
9. The reciprocating carrier-bar D and button-conductor D'', in combination with the supplemental detent f and reciprocating transverse bolt E, substantially as specified. 10
10. The head A, vertically-reciprocating bar D, carrying feed-plate D'', bolt D', and transverse-reciprocating bolt E, provided with a shank and spring E', in combination with the jaw B, spring-yoke F, jaws H, pivoted at g , and anvil I, provided with pin or stud h'' , all constructed, arranged, and operated substantially as and for the purpose set forth. 15
11. In a button-setting machine, the combination of a reciprocating button-carrier, a detent, f , the sliding bolt adapted to release the button from the carrier, and an upsetting-anvil, substantially as set forth. 20
12. The horizontally-reciprocating bolt having a cam-face, in combination with a vertically-reciprocating button-carrier provided with a cam-face, substantially as and for the purpose set forth. 25
13. In a button-setting machine, the magazine M, in combination with the split ring N, for the purpose set forth. 30
